UNITED STATES PATENT OFFICE.

CHESTER A. HOFF, OF AKRON, OHIO, ASSIGNOR TO THE AKRON LAMP COMPANY, OF AKRON, OHIO, A CORPORATION OF OHIO.

WINDOW CLEANER.

Application filed March 10, 1927. Serial No. 174,208.

This invention relates to devices for cleaning windows or the like, the particular object of the invention being to combine in a single implement, a sponge or swab for the application of a cleaning liquid, such as water, and a wiper or plurality of wipers or squeegees for the removal of the liquid. The entire device is arranged and combined upon a simple, effective holder capable of use either by hand or upon a pole to reach remote windows or portions of windows. One of the objects of the invention is to provide a simple clamping device for the sponge and a simple clamping device for holding the plurality of wipers so that one or the other may be used, each wiper serving as a means for clamping the other in position. Large and small wipers may therefore be mounted upon a single appliance so that a change may be made without difficulty. This is a valuable feature of the invention as it enables the workman to use the same device for cleaning large or small windows, mirrors or the like.

The device has other advantages permitting the housewife to wash windows effectively without placing her hands in the water. The holder may be quickly changed from a hand to a pole. It may be used for washing and polishing with equal effectiveness and is properly balanced between one side of the device carrying the sponge or swab and the other side the driers or squeegees. It may also be taken apart readily for cleaning or replacing either of the instrumentalities.

In the drawings in which the preferred form of the invention is shown:

Figure 1 is a plan view of the device;

Figure 2 is a side view;

Figure 3 is a cross section on the line 3—3 of Figure 1; and

Figure 4 is a cross section on the line 4—4 of Figure 1.

The device comprises a hollow, preferably tubular handle 1, which may be grasped in the hand or may be received over the end of a stick or pole. Near the upper end of the handle is a nut 2, which is fixed in position by crimping the handle as at 3—3 on either side thereof.

The upper portion of the device comprises a main supporting plate 5 which is provided with a narrow central or waist portion through which is stamped an aperture 6.

One side of the central plate is widened to provide a wide flaring extremity 7. Above this portion of the central plate is mounted a similarly shaped clamping plate 8 having its outer end over the portion 7 of similar shape and having its inner narrow end bent downwardly to form a flange 10 which rests upon the top of the central plate. A bolt 12 is rigidly secured in the clamping plate near the flange 10 and passes through the hole 6 and into engagement with the nut 2.

Between the outer ends 7 and 9 is received the sponge or swab 14 which is here shown as a strip of sponge rubber, the ends of the plates being turned downwardly to afford a better grip upon the sponge rubber. It will be noted that as the handle 1 is rotated upon the bolt the plate 8 is drawn toward the central plate rocking upon the part 10 as a fulcrum and thereby securely gripping the sponge.

The wipers or squeegees which are two in number are shown at 15 and 16, the former being a short wiper and the latter a longer wiper for narrow or wide surfaces. As the device is shown the short wiper is in position and the longer wiper in reserve. Each wiper consists of a strip of flexible rubber 17 having a narrow working edge and a heavier rear portion which is received within a metal backing strip 20, the edges of which are pressed together to grip the rubber.

In order to hold the wiper in place the central plate is formed at its outer extremity with two spaced, angularly offset fingers 21 which are struck upwardly from the central plate. Above the central plate is mounted a squeegee clamping plate 22 which is formed with two spaced angular clamping fingers 24 which correspond to the finger 21 but are oppositely positioned with respect thereto. It will also be observed that the fingers 21 and 24 are arranged in alternation.

The plate 22 is pivoted near the extremity of the central plate by means of an upwardly extending angular tongue 25 struck upwardly from the stationary plate 5 and passed through a hole 26 on the plate 22, and by a downwardly extending angular tongue 27 struck out from the pivoted clamping plate and projecting through a hole 28 on the stationary plate 5. This arrangement permits a limited working action of the plate 22 to permit the jaws formed by the fingers 21 and 24 to open sufficiently to

release the wiper held therein, it being noted that the jaws are shaped so as to fit the backing strip when clamped together. When the device is assembled the parts 5 and 22 can not be separated from one another.

The inner end of the pivoted clamp plate is provided with a locking extension 30 which is preferably formed of a separate metal plate having depending fingers 31 passing on either side of the central portion of the plate 5, and bent outwardly to form two jaws 32, parallel to the plate 5. When the plate 22 is depressed to clamp the wiper between the jaws 21 and 24, the second 15 wiper or the one not in use may be inserted between the jaws 32 and the under side of the stationary plate 5. The construction is such that pressure must be applied to the plate 22 to cause the jaws 32 to open sufficiently to permit the insertion of the idle 20 wiper, but upon release of the pressure the springy character of the metal in the plate, aided somewhat by the rubber in the wiper in position, causes the plate to exert a con-

stant pressure upon the two wiper members, 25 sufficient to hold them fixed in their respective positions. Pressure upon the upper surface of the plate 22 will release the wipers and permit replacement or interchange.

While the description and drawing have 30 been made quite specific it is apparent that the invention is subject to change and modification within the scope of the claim when fairly interpreted in view of the prior art applicable thereto.

What is claimed is:

A device for the purposes set forth comprising, a stationary plate having a jaw upon its outer end, a plate pivoted intermediate its ends upon the stationary plate, 40 a jaw upon one end of the plate adapted to cooperate with the first named jaw to clamp a wiper strip, and a secondary jaw upon the other end of pivoted plate adapted to cooperate with the stationary plate to hold a 45 locking strip or wedge for securing the first-named jaws in clamping position.

CHESTER A. HOFF.
